UNITED STATES PATENT OFFICE.

FENTON E. JUDSON, OF ANTIGO, WISCONSIN.

DESIGN FOR AN ANTIRATTLER.

SPECIFICATION forming part of Design No. 33,223, dated September 18, 1900.

Application filed August 21, 1900. Serial No. 27,523. Term of patent 14 years.

To all whom it may concern:

Be it known that I, FENTON E. JUDSON, a citizen of the United States, residing at Antigo, in the county of Langlade and State of Wisconsin, have invented and produced a new and original Design for Antirattlers, of which the following is a specification, reference being had to the accompanying drawings, forming part thereof.

10 Figure 1 is a perspective view of the invention. Fig. 2 is a section on the line 2 2 of Fig. 3. Fig. 3 is a rear elevation looking in the direction of the arrow x in Fig. 2. Fig. 4 is a plan view looking in the direction of 15 the arrow x^2 in Fig. 2, and Fig. 5 is a front elevation looking in the direction of the arrow x' in Fig. 4.

Similar characters of reference indicate corresponding parts in all the views.

20 The leading feature of the design consists in the configuration of the antirattler made

the subject of the accompanying illustrations, the said design presenting a rounding bar or main part a , at each end of which appears a wing-like figure or cheek b . Intermediate 25 the ends of the bar or body the design presents a middle member comprising a curved upper part c , lying rearward of the transverse line of the wings b , and a downwardly-projected part c' , lying below the bar or body a . 30

Having thus described my invention, I claim as new and desire to secure by Letters Patent—

The design for an antirattler, as herein shown and described. 35
In testimony whereof I have signed my name to this specification in the presence of two subscribing witnesses.

FENTON E. JUDSON.
